UNITED STATES PATENT OFFICE.

TAYLOR BURROWS, OF LONDON, ENGLAND, ASSIGNOR TO THE FLAX COMBING SYNDICATE, LIMITED, OF SAME PLACE.

COMBING-MACHINE.

SPECIFICATION forming part of Letters Patent No. 633,794, dated September 26, 1899.

Application filed December 29, 1897. Serial No. 664,402. (No model.)

To all whom it may concern:

Be it known that I, TAYLOR BURROWS, engineer, a subject of the Queen of Great Britain, residing at 88. Upper Kennington Lane, 5 London, England, have invented certain new and useful Improvements in or Relating to Noble Combing-Machines or the Like, of which the following is a specification.

This invention has for its object improvements in or relating to "Noble" combing-machines or the like, primarily, to adapt the same for combing vegetable fibers, such as flax or china-grass; and it consists of certain novel features hereinafter described and claimed.

Reference is had to the accompanying drawings, in which the same parts are indicated by the same letters throughout the several views.

Figure 1 is a plan or diagrammatic view 20 in plan of a Noble combing-machine having the present improvements applied thereto. Fig. 2 is a side view or elevation looking in the direction of the arrow 1, Fig. 1. Figs. 3 to 6 are detail views of the "feeding" arrangement, Fig. 3 being a local detail view, 25 on an enlarged scale, showing one arrangement for feeding according to the present invention; Fig. 4, a local plan view of Fig. 3. Fig. 5 is a sectional view taken on the line 5 5 30 of Fig. 6, and Fig. 6 is a sectional view taken on the line 6 6 of Fig. 5.

A bobbin, reel, or spool *a* (which will hereinafter be referred to as a "reel") is used, having a spindle or axle passed centrally through the same, the projecting ends *a'* of which form the axes on which said reels revolve, as shown in the drawings, or these axes *a'* may be simply trunnions fixed to the side cheeks of the reel *a*, or the slivers may be wound onto circular tubes or rods, (without flanges, if desired.) Four or other suitable number of slivers *b* are wound parallel onto each said reel and are advantageously tightly wound thereon, so as to obtain the double advantage 45 of (first) getting more material on each reel, and (second) it is found that the fiber, especially flax or china-grass, will thereby run off or unwind very much better when thus tightly wound. The projecting ends or trunnions *a'* of this reel *a*, on which the slivers are wound, rest when on the combing-machine

in V-shaped or approximately V-shaped bearings or holders *c*, so that the weight of the reel *a* at its full charge being heavy consequently presses the ends *a'* down, so that the latter are wedged between the converging sides of the V-shaped holder or bearing *c*. These V-shaped bearings *c* may be mounted on short stays or supports *c'*, bolted, screwed, or otherwise suitably fixed to and carried on or by the circular revolving frame *d* of the Noble or the like combing-machine and are carried around therewith. This arrangement of V-shaped bearings carried in fixed supports on the revolving part of the machine is shown in detail in Figs. 3 and 4, and in this case the feed-plate *e* is carried on a bracket *e'*, pivoted at *d'* to the aforesaid revolving frame *d*. This pivoted bracket *e'* has an extension *e*², which comes to rest against the under side of the revolving frame *d*, and thereby prevents the bracket *e'* from turning outward on the pivot *d'* beyond the position shown in Fig. 3. This bracket *e'* also carries another arm projecting downward below the pivot *d'*, and as this downwardly-projecting arm *e*³ is carried around with the revolving frame *d* such arm *e*³ rides against a fixed cam-like surface *e*^X, rigidly mounted on a fixed part of the framing of the machine in the path of travel of said arm *e*³. Consequently said arm *e*³ is forced by the cam *e*^X from the position shown in full lines in Fig. 3 into the position shown in dotted lines, and thus the feed-plate *e* is raised and draws a certain amount of sliver *b* off the reel *a*, and then the arm *e*³ passes clear of the fixed cam-like surface *e*^X and the feed-plate drops back, and thus leaves a small amount of slack in the sliver *b*, which thus permits the feeding operation to readily take place, or said V-shaped bearings *c* may be carried on rocking supports—for instance, a forked device consisting of the forked arms *f'* *f*', pivoted at *f*² *f*² in supports *f*³, fixed to the revolving frame *d*, the forked arms *f'* *f*' converging and terminating in the single arm or lever *f*, which latter, extending inwardly, (i.e., toward the center of the machine,) rides under an inclined plane or device *f*^X, fixed (to some stationary part of the machine) in the path of travel of said arm or lever *f*. Thus as each lever *f* in its path of travel rides un-

der the inclined plane f^x thereby each said lever f is depressed, and consequently the forked ends f' thereof are raised, and thereby the reel a in the bearings c is lifted bodily 5 just before the feed takes place, as shown in Fig. 2, and thus the sliver between the ball and the feed-boxes x is thrown slack, as shown in dotted lines in Fig. 5, and the reel a is maintained in this raised position until after 10 the feed has taken place, and then the lever f passes clear of the fixed inclined plane or device f^x , whereupon the forked ends f' and the reel a supported therein are lowered, and consequently the amount of the sliver b absorbed in the last feed is now unrolled off 15 said reel a , and then the latter comes to rest again in its V-shaped bearings c , which bearings prevent any excess of unwinding taking place, and consequently maintain the slivers 20 in a taut condition. Thus in a circular combing-machine of the character illustrated in Fig. 1, where the material is fed twice in the course of each revolution, consequently the reels a are each raised and lowered twice in 25 the course of each revolution of the machine.

Having thus described my invention, what I claim, and desire to secure by Letters Patent of the United States, is—

1. In a combing-machine the combination 30 of a feed-plate, a spool or reel, V-shaped bearings for said reel and means for periodically varying the distance between said plate and reel, substantially as described.

2. In a combing-machine, the combination of a spool or reel, V-shaped bearings for said reel and means for periodically raising and lowering said bearings and reel substantially as described. 35

3. In a combing-machine, the combination of the frame of the machine provided with one or more cam-surfaces, a revoluble plate above said frame, a lever supported by said plate, V-shaped bearings carried by said lever and a spool or reel mounted in said bearings substantially as described. 40

4. In a combing-machine, the combination of the frame of the machine provided with one or more cam-surfaces, a revoluble plate, a bracket mounted on said plate, a forked lever pivotally mounted on said bracket, V- 45 shaped bearings carried by said lever and a spool or reel, substantially as described. 50

5. In a combing-machine, the combination of the frame of the machine provided with one or more cam-surfaces, a revoluble plate, a perforated feed-plate carried thereby, a bracket 55 depending from said revoluble plate, a forked lever pivoted on said bracket, V-shaped bearings carried by said forked lever and a spool or reel mounted in said bearings, substantially as described. 60

TAYLOR BURROWS.
